(57) **CLAIM**

We claim the ornamental design for a shelf for refrigerator, as shown and described.

DESCRIPTION

FIG. 1 is a perspective view as seen from the top, front, and left side of a shelf for refrigerator showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view as seen from the top, front, and left side of the shelf for refrigerator shown in FIG. 1 shown in use in a refrigerator.

The broken lines shown in the drawing disclosure are for illustrative purposes only and form no part of the claimed design.
